UNITED STATES PATENT OFFICE.

THEOPHILE EUPHRAT, OF ROWAYTON, CONNECTICUT, ASSIGNOR TO JAMES A. LOGAN, OF BROOKLYN, NEW YORK, AND THE EUPHRAT MANUFACTURING COMPANY, OF NEW YORK, N. Y.

GUARD AND SHADE ATTACHMENT FOR WINDOWS.

SPECIFICATION forming part of Letters Patent No. 693,957, dated February 25, 1902.

Application filed March 9, 1901. Serial No. 50,441. (No model.)

To all whom it may concern:

Be it known that I, THEOPHILE EUPHRAT, a citizen of the United States of America, and a resident of Rowayton, county of Fairfield, 5 State of Connecticut, have invented certain new and useful Improvements in Guard and Shade Attachments for Windows, of which the following is a specification.

My invention relates to the guard and screen attachment for windows on which Letters Patent of the United States were granted to me June 19, 1894, No. 521,607; and it consists of further improvements in the said guard and screen attachment, as hereinafter described, 15 reference being made to the accompanying drawings, in which—

Figure 1 is partly a front elevation and partly a sectional elevation of a window having guard and screen attachments contrived 20 in accordance with my present invention. Fig. 2 is a vertical elevation on the line $x-x$ of Fig. 1. Fig. 3 is a plan view of the bar by which the rods of the guard are connected to the lower window-sash. Fig. 4 is partly a 25 vertical section and partly a front elevation of part of the lower sash.

As in my said former patent I represent the guard for protection from burglars and for preventing children from falling out of the 30 window as consisting of a series of parallel metallic bars or rods a , suspended from the lower rail b of the sash through holes in the sill c of the window-frame into the inclosed space below the sash and being of such length that 35 they will not escape from the holes when the sash is raised to the highest point, so that being confined at the lower ends in the sill and at the upper ends in the sash they form a substantial protecting-grate, which, being 40 equally as serviceable as the permanently-attached grates of common use, is concealed from view when the sash is closed. Instead of the metallic rods any reticulated or open fretwork structure may be used, and they 45 may be made in any desired form of ornamental character. My present improvement in respect to this part of the invention consists in providing for greater convenience in washing the outsides of the windows from the 50 inside and for free course through the lower

part of the window for any purpose by so connecting the guard to the sash that it may at any time be readily detached and left remaining at the bottom of the window, and the sash may be readily raised independently of 55 the guard, and the guard may be as readily attached to the window again whenever desired. For this purpose the guard may, instead of being permanently attached to the sash-rail, as heretofore, be detachably connected in various ways. For example, turn-buttons, as o , carried on the lower ends of pivots p , fitted vertically through the lower sash-rail and having a lever q , knob, or other device on the upper end for turning them, 60 may engage with hook-catches s , attached to the upper side of a bar t , to which the rods a are attached instead of being attached directly to the rail, as before, or any other devices, as jaws u of a desk-lock, such as engage 65 through a slot w in the bar t and are released by a key inserted at v , may be employed, the latter device being preferable when the fastening device is accessible to children and liable to be carelessly disconnected by them. 70 Thus the guard may be hooked on or dropped off, as occasion may require. In this case the spring curtain-roller d for carrying the screen or curtain f is mounted under the top e of the window instead of above it, as before, this being 75 a preferable arrangement when my improvements are put up in buildings previously completed; but I may also, but at a little more expense, locate said roller as before, the latter being a preferable arrangement for concealing the roller from view, but it may also be concealed as herein placed by a molding placed in front.

As in my former patent, the curtain or screen f is connected by its bar g and cords 90 h with the lower sash-rail b , said cords passing under pulleys i , located at the bottom of the window, so that raising the window will pull down the screen; but instead of mounting the pulleys on weights suspended in the 95 bights of the cords in the space below the window to follow up and down as the sash is shifted up and down I now mount said pulleys on fixed pivot-studs j , with openings k through the window-sill c , adapted for the 100

slack of the cords to drop therethrough for being concealed when the screen or curtain is to be pulled farther down than it may be pulled by its connection with the sash. Thus 5 I dispense with the weights before used and save their expense besides avoiding some noise and friction and unnecessary wear on the cords.

The cords *h* may be detachably hooked onto 10 the screen-bar *g* in any approved way, so as to be readily unhooked at any time it may be desirable to allow the screen or curtain to remain rolled up when the lower sash is raised.

15 When it is desired to pull the screen entirely down to the bottom of the window, it may be secured by a catch *m* in engaging any suitable catch *n* on the window-sill. The cords *h* will then drop through the slots *k*.

20 The pulleys *i* are set down in the slots *k* flush with the top of the window-sill and the side walls thereby serve as guides to direct the cords onto the pulleys when drawn up taut against them.

25 The edges of the curtain or screen are fitted on guide-grooves *y*, suitably provided in the window-frame.

What I claim as my invention is—

1. The combination with the lower sash of 30 the self-raising curtain-roller and curtain or screen, pulleys located on fixed pivots at the

bottom of the window, cords connecting the lower end of the curtain or screen and the lower rail of said lower sash under the pulleys, thus allowing the curtain to be pulled 35 down independently of the sash to which it is connected, and a passage through the window-sill for the drop of the slack of the cords when the curtain or screen is pulled below the limit of its movement by the sash. 40

2. The combination with the lower sash of the self-raising curtain-roller and curtain or screen, pulleys located on fixed pivots at the bottom of the window, cords connecting the lower end of the curtain or screen and the 45 lower rail of said lower sash under the pulleys, thus allowing the curtain to be pulled down independently of the sash to which it is connected, and a passage through the window-sill for the drop of the slack of the cords 50 when the curtain or screen is pulled below the limit of its movement by the sash, said pulleys arranged to set into said slots, and the latter arranged for guards to confine the cords on the pulleys. 55

Signed at New York city this 4th day of March, 1901.

THEOPHILE EUPHRAT.
